L. Becker

UNITED STATES PATENT OFFICE.

LEGRAND BECKER, OF RONDOUT, NEW YORK.

COMPOUND JACK.

SPECIFICATION forming part of Letters Patent No. 314,560, dated March 31, 1885.

Application filed February 10, 1885. (No model.)

To all whom it may concern:

Be it known that I, LEGRAND BECKER, of Rondout, in the county of Ulster and State of New York, have invented a certain new and Improved Compound Jack, of which the following is a specification.

This invention relates to an improvement in compound screw-jacks; and it consists in the novel combination of a double screw-jack 10 with a lever and fulcrum, and is especially adapted for locomotive-works for taking out and putting in the springs of a locomotive. The fulcrum, being a screw, can thereby be adjusted to different positions, as may be required by difference in the equalizer to which 15 they are to be fastened.

The method of using this invention for taking out or putting in locomotive-springs is by 20 passing the slotted end of the fulcrum over the equalizer of the locomotive and putting a pin through under it. The end of the lever 25 that presses on the spring is notched to prevent it from slipping ahead, and the jack-screw is then turned and the spring is pressed to its place. I attain these objects by the mechanism illustrated in the accompanying drawings, in which—

Figure 1 is a side view of two compound jacks embodying my improvement. One is in 30 position for raising a spring and the other in position for lowering a spring. Fig. 2 is a top view of the same. Fig. 3 is a section view of the same.

Similar letters refer to similar parts throughout the several views.

In Fig. 1 the lever A is open at one end, as shown in Fig. 2, and two revolving nuts, E E, are pivoted into it. The pivots F F pass

through the lever, as shown in Fig. 1. The end of the lever that is to lift or lower the 40 spring S is notched, G, to prevent it from slipping. The screw H has a slotted head, B, to pass over the equalizer P of a locomotive, as shown in Fig. 1, and has holes X X for a pin, K, to pass through under the equalizer P, to 45 receive the strain when the screw C or H is turned to lower or raise the spring S. The screw C is pointed at one end, and has a square head, N. The head is also pointed, so that the screw can be used either end. The point is 50 to keep it from slipping.

In Fig. 2 the compound jack shows the revolving nuts E E with the pivots F F, and in Fig. 3 a sectional view of the screw H is illustrated, showing slotted end B over the equalizer P and the pin K under it. The screw H is pivoted into the slotted head B to turn, and is riveted, as shown at D, and has a square head to turn it by.

Having thus described my invention, what 60 I claim as new, and desire to secure by Letters Patent of the United States, is—

1. The lever A with slotted end and with the notched end G, all as shown and specified, and for the purposes set forth. 65
2. The combination of revolving nuts E E with the pivoted ends F F.
3. The slotted head B, having holes X X, and the pin K, in combination with the screw C and H, and the lever A with the notched 70 end G, as described.

LEGRAND BECKER.
